(57) **CLAIM**

The ornamental design for a combined bench and toy train, as shown and described.

DESCRIPTION

FIG. 1 is a perspective of a combined bench and toy train of the present invention;

FIG. 2 is the perspective of the combined bench and toy train having elements positioned in an alternate arrangement;

FIG. 3 is a front elevation of the combined bench and toy train, the rear elevation being identical thereto;

FIG. 4 is a top plan of the combined bench and toy train;

FIG. 5 is a left side elevation of the combined bench and toy train, the right side elevation being identical thereto; and,

FIG. 6 is a bottom plan of the combined bench and toy train. The broken lines represent portions of the article that form no part of the claim.
